CLASSIFIER MECHANISM

Charles H. Scott, Westport, Conn., assignor to The Dorr Company, Inc., New York, N. Y., a corporation of Delaware

Application January 26, 1938, Serial No. 186,942

20 Claims. (Cl. 198—224)

This invention relates to classifiers or stratifiers in which, and by which, a bath of a liquid-solids mixture, usually called a pulp, is separated into an emerged coarse solids fraction and an overflowed suspension of a fines fraction. More in particular, this relates to improvements in the solids raking bladed mechanism of which a plurality of reciprocating rakes or blades convey stepwise settled solids to emergence up the partially submerged sloping bottom or deck of the tank.

In the layout of ordinary classifiers the maximum depth of the bath is usually fixed by the degree of classification to be attained so that a critical limit for the slope of the deck and the required depth of the bath determine the requisite length of the machine to get the rake product to be discharged in emergence, and consequently depending upon the required depth of submergence such length may become excessive, and the machine unwieldy, heavy, and expensive in first cost, operation and space requirements.

The critical slope of the tank in turn depends upon the back flow or slippage of the material being raked upwardly along the deck, because the permissible retrograde flow of the burden of each raking blade must be compatible with a requirement for fair raking and conveying efficiency.

Accordingly, the invention contemplates the design of a steep-slope classifier in which the degree of slope may be chosen independent of potential back flow or slippage of the material; in which maximum raking and conveying efficiency is attained within a minimum of classifier length; and in which the rake product is elevated to a desired point of delivery within a restricted space and without impairing the quality of separation intended to be obtained by the classifier.

Therefore, one object of the invention is the design of an efficient steep-slope classifier.

This object is attained broadly by intercepting and detaining or preventing retrogression of the individual piles of solids or burden engaged by raking blades during the period of their release from the raking blades incident to each elevated and non-raking or idle return movement thereof by the employment of interceptor plane face portions having a general extent at right angles or perpendicular to the plane of the sloping deck or bottom of the tank.

In one manifestation of the invention, this is realized through the coaction and kinematic coordination of a set or sequence of reciprocable,

spaced, solids-raking blades with a corresponding set of solids intercepting and detaining gates or stopper blades, the coaction being that at the end of a raking stroke the detaining gates or stoppers descend directly in front of and sufficiently close to the raking blades to intercept and hold the respective piles or loads of solids then engaged by each individual raking blade just long enough to allow for the return rearward elevated movement of the raking blades. The raking blades then descend directly in front of the detaining gate or stopper blade to engage a new load of solids thus held ready for it by the stopper, whereupon the stopper blades rise so that the next phase in the cycle of stepwise procession or progression of the solids may be effected by the raking blades. Novel features lie in the character of the raking diagram and the control mechanism for carrying them out.

Accordingly, and aside from the principle of stopper blade action, the invention also has to do with an improved rake actuating mechanism for carrying out a suitable and desirable diagram of the raking cycle and which is particularly suited in view of the action of the stopper blades. More in particular, this raking diagram is characterized by a steep or perpendicular descent at the end of the elevated return stroke of the rake, relative to the sloping tank bottom.

Accordingly, it is a feature of the improved rake actuating mechanism as such that the up and down positioning movement of the raking structure is effected by means of swingable track members journaled relative to the tank, each track member having individually and operatively associated therewith a rake suspension point or rather a track roller representing such a suspension point. More specifically, the actuation of such a rake suspension point is effected by way of a bell-crank-like member, one arm of which constitutes the swingable track, the other arm being actuated through cam control linkage from a drive shaft, the rotation of which also produces the longitudinal reciprocating component movement of the raking cycle.

An advantage is that the provision of control cam means will impose upon the drive a minimum of load necessary for lifting and holding the rake in lifted position during the elevated return stroke of the structure.

It is among the advantages that a steep-slope classifier according to this invention combines with a rotary grinding mill to make a compact closed circuit grinding system for metallurgical or other similar purposes, inasmuch as the steep-

slope construction of the classifier permits the point of rake discharge to be located close to and sufficiently high above the feed end of the mill to permit substantially direct gravitation thereto 5 of recirculating load within a minimum of space and without the employment of auxiliary lifting devices.

The invention possesses other objects and features of advantage, some of which with the foregoing will be set forth in the following description. In the following description and in the claims, parts will be identified by specific names for convenience, but they are intended to be as generic in their application to similar parts as 10 the art will permit. In the accompanying drawings there has been illustrated the best embodiment of the invention known to me, but such embodiment is to be regarded as typical only of many possible embodiments, and the invention 15 is not to be limited thereto.

The novel features considered characteristic of my invention are set forth with particularity in the appended claims. The invention itself, however, both as to its organization and its method 20 of operation, together with additional objects and advantages thereof, will best be understood from the following description of a specific embodiment when read in connection with the accompanying drawings, in which:

30 Fig. 1 is a plan view of a twin compartment classifier, each compartment equipped with solids raking and solids intercepting bladed mechanism.

Fig. 2 is an end view taken upon Fig. 1.

35 Fig. 3 is an enlarged diagrammatic view illustrating raking in a substantially triangular diagram.

Figs. 4 to 7 show various operating phases of the solids conveying mechanism according to the 40 invention.

Fig. 8 is a skeleton perspective view of the raking mechanism according to the invention.

Fig. 9 is an enlarged detail of a connecting rod 45 capable of automatic resilient telescoping fore-shortening in the event of load obstruction or the like.

The classifier shown in Figs. 1 and 2 is a twin compartment unit comprising the classifier compartments A and B. Each compartment is 50 equipped with substantially the identical conveying mechanism according to the invention so that a description of one compartment and its mechanism will suffice.

The tank as more clearly illustrated in Fig. 4 55 has a sloping bottom 10 or deck partially submerged, side-walls 11, and an end wall 12 having an overflow weir 13, a bath or solids suspension in the tank being indicated by the numeral 14 and the level of which is defined by the weir 13.

60 The mechanism as herein shown by way of example comprises a rake structure 15 consisting of a sequence of raking blades 16 having their ends fixed or welded to a pair of beams or stringers 17 formed with an upper pair of hangers 65 ers 19 and a lower pair of hangers 20.

70 Cooperatively associated with the rake structure 15 is an auxiliary bladed structure or interceptor structure or stopper assembly 21 having interceptor faces substantially embraced by the rake structure 15 in a peculiar manner hereinafter to be described. The auxiliary structure 21 has a sequence of interceptor or stopper blades 22 spaced at intervals which are substantially equal to those of the raking blades 16. The interceptor blades 22 have brackets 23 whereby they 75

are connected with a pair of beams or stringers 24.

The auxiliary bladed structure 21 is arranged to operate substantially within the confines of the rake structure 15 in a manner herein more 5 clearly to be described.

There will now be described actuating mechanism whereby to effect the solids conveying reciprocating movement of the rake structure 15, as well as actuating mechanism effecting up and 10 down solids intercepting movement of the auxiliary bladed structure 21, and finally there will be described means for driving and controlling both structures 15 and 21 in a desired functional coordination.

The solids conveying cyclic movement of the raking structure 15 results from a horizontal and a vertical component movement given it by the actuating mechanism. The vertical component movement or up and down positioning movement 20 is realized due to swingable or supporting track members and upon which the upper and the lower rake hangers respectively may operate by way of track rollers 27 and 27a respectively. A track member 25 is fixed upon a rocker shaft 28 the fulcrum portion of which is operatively supported by way of journals upon the sides of the classifier tank, and the shaft 28 has an upwardly extending arm 29 disposed at an angle relative to the track member 25. Similarly a track member 26 has 30 an upwardly extending arm 30. Thus each track member 26 and 27 respectively constitutes with its associated arm 29 and 30 respectively in effect a bell crank member. A reach rod 31 interconnects the free ends of arms 29 and 30. A link 32 connects arm 29 with a rocking lever 33 fixed upon a rocker shaft 34 which has fixed thereto a cam lever 35 carrying a cam roller 35a normally engaging upon and controlled by a rotary cam member 36 having a relatively protruding or outlying cam portion 37 and a relatively recessed or inlying cam portion 38. The cam member 36 is fixed upon a main actuating shaft 39 journaled upon the classifier tank and having a crank portion 40 from which the horizontal component movement of the raking member is controlled, and which is distinguishable from the vertical component—or up and down positioning movement of the raking member.

The horizontal component movement of the 50 raking member is controlled by the crank portion 40 through a connecting rod 41 which pivotally connected as at 42 with the rake member 15 by way of arm portions 43 fixed upon a transverse bar or rod 44 which rigidly interconnects 55 the hanger portions 19 of the rake member 15.

The main actuating shaft 39 is herein shown to be driven by a set of gears 45 and 46.

The auxiliary bladed structure or solids interceptor member 21 has its one end portion supported through a link 47 from a bell crank 48 fulcrumed at 49 and having arms 50 and 50a. Correspondingly, the lower section of the auxiliary bladed member 21 is suspended through a link 51 from a bell crank lever 52 fulcrumed at 53 upon the classifier tank and consisting of arms 54 and 55. A reach rod 56 interconnects the free end portions of arms 50a and 55 of respective bell crank levers 48 and 52. A link rod 57 connects the bell crank lever 48 with a rocking lever 58 fixed upon a rocking shaft 59 which in turn has fixed upon it a cam lever 60 carrying a cam roller 61 normally engaging upon the cam member 36. The two cam portions 37 and 38 are substantially complementary portions of the 75

cam member 36. The active or peripheral cam faces of the cam portions 37 and 38 constitute an outlying arc portion of a relatively larger diameter 37a and an inlying arc portion of a relatively smaller diameter 38a respectively, and there are transitional portions or steps or shoulders 37b and 38b respectively between the active cam portions.

The cyclic movement of the raking member 15 or what is known as the rake diagram is shown in Fig. 3 to be in the nature of a substantially triangular path 62 comprising a rectilinear branch 63 parallel to the bottom of the classifier tank and which corresponds to the solids raking stroke of the movement, an ascending branch 64 corresponding to the non-raking return stroke, and a branch 65 which represents a direct or steep drop or perpendicular descent with respect to the tank bottom of the raking blades from their highest or final non-raking position to their initial raking position. Raking blades are shown in this diagram in various raking, as well as in non-raking positions.

The various operating positions of the mechanism controlling the raking movement are shown in Figs. 4, 5, 6, and 7.

Fig. 6 shows the highest non-raking position of the raking member 15, and which is kinematically defined by a position of the cam member 36 when the cam roller 35a has reached the end of the protruding cam portion 37 and is about to drop down the step or shoulder 37b onto the face of the recessed cam portion 38. Accordingly, at this time through arm 33 and rods 32 and 30 the swingable tracks 25 and 26 are held in their highest angular position, and the track rollers of the rake hangers 19 and 20 in turn are held in their highest position upon the tracks due to the then position of the crank 40 and connecting rod 41 controlling the position of the rake member 15 in a horizontal sense.

Subsequently the cam roller 35a drops onto the recessed cam portion 38 which movement corresponds to the branch 65 of the rake diagram of Fig. 3. This causes the swingable track members 25, 26 to drop and thereby to establish the beginning of the raking stroke a phase of which is shown in Fig. 7. The lowered position of the rake member during the raking stroke is maintained as long as the cam roller 35a engages the rotating recessed cam portion 38 while concurrent rotation of the crank 40 through connecting rod 41 pulls the rake through its solids conveying stroke according to branch 63 of the rake diagram (Fig. 3).

Towards the end of this raking stroke the rotation of the cam member will compel the cam roller 35a to mount up the cam shoulder 38b onto the protruding cam portion 37 thus causing the tracks 25, 26 to be swung upwardly as the track rollers 27 and 27a of the rake hangers reach the inner ends of their tracks proximate the pivotal or fulcrum point thereof. The tracks are held in their upper position by the protruding cam portion 37 during the further rotation of the cam member 36 and concurrently with such cam rotation the crank 40 through connecting rod 41 will cause the rake member 15 to be moved towards the outer end of the then raised tracks 25, 26 which movement corresponds to the inclined ascending branch 64 of the rake diagram (Fig. 3).

The movement of the associated auxiliary bladed member 21 is a simple up and down movement and cam controlled through the cam

roller 61, and timed to certain phases of the movement of the raking member 15, both movements being controlled by the identical cam member 36. As will be seen the cam rollers 35a and 61 are disposed at substantially diametrically opposed points of the cam member 36, so that they will alternately be engaged by the protruding cam portion 37 and the recessed cam portion 38 respectively. In other words, while the cam roller 35a engages the protruding cam portion 37 the cam roller 61 will engage the recessed cam portion 38, and vice versa. Accordingly, the coordination and timing of the movements of the rake element and of the stopper blade element is such that at the end of a raking stroke the stopper blades 22 will descend in a sudden drop in front of and close to the raking blades 16; in other words, the stopper blades will descend when the raking blades have reached a point *a* in the rake diagram (Fig. 3), and they will thus intercept the loads held by the raking blades before the same rise away from the bottom and they will continue holding the loads to prevent their slippage until the raking blades have returned by way of point *b* in the rake diagram to the point *c* at which point each raking blade in turn will intercept a preceding load to permit the stopper blades to rise and in order to advance the load another step up the classifier slope to point *a* of the rake diagram.

With respect to the up and down positioning movement of the longitudinally reciprocating rake structure 15, it will be understood that the path of this movement is substantially determined by the angular movement of the track members 25 and 26, which angular movements are herein shown to take place at the ends of the raking stroke. In other words, the track members are caused to swing upwardly when the track rollers 27 and 27a have reached the position proximate to the pivotal point of the tracks, in which position the power required for lifting the rake is a minimum, due to the shortness of the leverage of the tracks at that point. In this extreme upper angular position the tracks are held, due to the engagement of the cam roller 35a up the arcuate cam face 39 so that during the phase of the elevated return stroke no rake holding power is required from the drive mechanism. That is to say, as the track rollers then move towards the outer ends of the tracks in performing their elevated return movement, the weight of the rake structure is intercepted as manifested by the pressure of the cam roller upon the cam face, and hence during this phase it does not affect the torque required of the cam drive shaft 39 during the return stroke phase of the raking cycle.

With respect to the up and down positioning movement required of the stopper blade member 21, it should be noted that this movement is herein and by way of example shown to be determined by a guide member 67 fixed upon the tank wall, and upon which guide member operates a guide roller 68 mounted on the stopper blade member 21.

In order to avoid injury or breakage in the machine from overstressing, it may be due for instance to jamming of the raking structure on account of congestion of solids in the tank or of solids or the like getting caught between the raking and the stopper blades, or for any other reason, there is provided in this improved rake actuating mechanism a give or resiliency, and which is herein shown to be realized in the special

construction of a resiliently contractable drive or connecting rod 41 (see detailed Fig. 9). Accordingly, this connecting rod 41 is of a telescoping nature and it has a fixed and limited maximum length of expansion during the raking stroke, but will resiliently foreshorten under compression. Accordingly, the example construction shown in the detailed Fig. 9 comprises a cylindrical portion 69 and a plunger portion 73, both limited relative to each other with respect to the length of expansion by way of a block 71 and a plunger head 72. A closure piece 73 is slidable in the open-ended portion of the cylindrical portion 69, and it is adjustably fixed with respect to the plunger rod 18 by way of lock nuts 74. Compression spring 75 occupies the angular space between the plunger rod and the surrounding cylindrical portion and it is endwise confined between the block 71 and the sliding closure portion 73. The head of the connecting rod is indicated by the numeral 76, and it is the one that operatively connects with the crank 40 of the cam drive shaft 39, whereas the opposite end portion is indicated by the numeral 77 and it is the one that attaches to the arms 43 that are fixed with respect to the rake hangers 19.

It will be seen that in order to obtain the desired coaction of the two bladed members and their efficient cooperation, to wit of the raking member 15 and of the interceptor bladed member 21, it is desirable that the spacing of the raking blades 16 be equal to the spacing of the stopper blades and approximately equal to and preferably not larger than the length of the raking stroke of the classifier.

The number of stopper blades 22 to be provided does not necessarily depend upon the number of raking blades 16, that is to say, not each raking blade 16 must needs have a stopper blade 16 associated with it. It depends upon factors of operation and structure, for instance upon the degree of slope of the tank bottom, how many stopper blades should preferably be provided and in what locality. However, a particularly effective point for the location of a stopper blade is in the zone of emergence of the solids on the deck, because of the tendency of the backwash of the liquid in this zone to drag solids about to emerge back into the bath.

50 I claim:

1. A classifying apparatus having a tank for holding a liquid-solids bath from which settle solids that are adapted to be removed upwardly along the sloping bottom of the tank, and having a rake structure movable in a cyclic operating path in a manner to effect the stepwise movement of said solids, and having rake reciprocating means for imparting longitudinally reciprocating movement to the rake structure, and having track means for the rake structure which track means are positionable to enable said rake structure to perform an upward forward solids raking stroke and an elevated non-raking return stroke within its raking cycle; and furthermore having track positioning means operatively associated with said rake reciprocating means; characterized by the fact that the track means are provided upon and by a swingable arm having an axis stationary relative to the tank and controlled by said track positioning means, to position said track means substantially parallel to the sloping bottom during the raking stroke, and to move the track means to an upwardly shifted angular position at the end of said raking stroke.

75 2. Apparatus according to claim 1 wherein the

track-means is swung into its uppermost angular position when the rake-structure is in the region proximate its most forward position.

3. Apparatus according to claim 1 wherein the operative arrangement of the track-positioning means with respect to the rake-actuating means is such that the track-means is swung into the uppermost angular position when the rake-structure is in the region proximate its most forward position and when the track-engaging means of the rake-structure is in the position proximate the pivotal point of the track-means, and wherein the construction of the track-positioning means is such that the track-means is held in the uppermost angular position during substantially the entire return stroke of the rake-structure and in the lowermost angular position during substantially the entire forward raking stroke of the rake-structure and in a manner whereby the track-means then parallels the inclined deck.

4. Apparatus according to claim 1, in which the swingable track-means comprises a swingable track member for lending support to one section of the rake-structure and a similar track member for lending support to another section of the rake-structure longitudinally-spaced from the former section.

5. Apparatus according to claim 1, in which the swingable track-means comprises one pair of transversely spaced swingable track members for lending support to one section of the rake-structure.

6. Apparatus according to claim 1, in which the swingable track-means comprises a bell-crank-like member one arm of which provides a swingable track; in which the track-positioning means comprises a link engaging the other arm of said bell-crank-like member; and in which said link is reciprocated through the action of a rotary cam member designed to effect a relatively sudden rise and a relatively sudden drop of the track member at the respective ends of the raking stroke.

7. Apparatus according to claim 1, in which the swingable track-means comprises longitudinally spaced bell-crank-like members, each of which has an arm providing a swingable track and an arm serving as a swingable track-positioning arm and in which the track-positioning means comprises linkage connecting the free ends of said swingable track-positioning arms.

8. An apparatus according to claim 1 in which journals are provided stationary with respect to said inclined deck whereupon said swingable arms are pivotally supported so that the pivotal axis of each said swingable arm extends horizontally and transversely; in which a horizontally and transversely extending main drive shaft carried in journals stationary with respect to said inclined deck; in which the rake-reciprocating means are operated from said drive shaft to move the rake-structure longitudinally back and forth along said swingable track-arms; and in which the track-positioning means are operated from said shaft functioning in timed relationship with respect to the rake-reciprocating means to swing said arms and the tracks provided thereby successively to the lower angular position in which the rake-structure derives support proper for the forward longitudinal raking stroke upwardly along said inclined deck, and into an upper angular position in which the rake-structure derives support for the elevated return stroke thereof.

9. A classifier comprising a tank for receiving and holding liquid and solids material to be

classified and having a sloping bottom, marginal side walls and a deep end wall extending upwardly from the sloping bottom, and an overflow weir provided in the region of the deep end 5 thereof that determines the normal operative level of the liquid within the tank; a drive shaft carried by journal means fixed in relation to the tank and provided with a main crank and with a cam means both of which are movable with the 10 shaft; a rake-structure having longitudinally spaced transversely extending blades and provided with track-engaging members through the medium of which the rake-structure is reciprocally supported upon and carried by tracks provided on the swingable track arms hereinafter referred to; lever constructions of which the fulcrum portions derive support from journal members, normally fixed as to position with respect to the tank having swingable track arms providing the tracks upon which said track-engaging members rest and along which said track-engaging members have forward and return reciprocatory movements and having link-actuated swingable track-positioning arms serving as the 20 medium through which the swingable tracks are angularly positioned which said lever constructions are disposed at elevations such that the tracks are at all times essentially above the normal level of the liquid within said tank; a main connecting rod connected to and actuated by the main crank and having a pivoted driving connection with the rake-structure provided for successively imparting forward and return longitudinal reciprocating movements to the rake-structure incident to the operating of the drive shaft; and a track-positioning linkage actuated from said cam-means and having pivotal connections to the free ends of the aforesaid link-actuated arms; said cam means being constructed 30 and arranged with respect to the main crank so that as the apparatus functions said cam-means and the linkage actuated therefrom will through the medium of said link-actuated arms cause the swinging of the tracks from the lower angular 35 positions therefor at a time when the track-engaging members of the rake-structure are near the pivotal axes for the track arms and will later cause a downward swinging of the tracks to substantially the lowermost angular positions 40 therefor and more particularly by the time the forward raking movement is about to take place.

10. A classifier as defined in and by claim 9, in which the lever constructions are longitudinally spaced and provide constantly parallel 45 swingable tracks, and in which the longitudinally spaced lever constructions include swingable track-positioning arms the free ends of which are connected by a longitudinally extending link.

11. Classifying apparatus having an inclined 50 deck; a reciprocable rake-structure having longitudinally spaced transversely extending raking blades movable in cyclic paths to effect longitudinal step by step movements of raked material upwardly and forwardly along said inclined deck; 55 a stopper construction having longitudinally spaced transversely extending blades for intercepting material therebetween and common means for actuating in timed relationship said rake-structure and said stopper construction by 60 imparting to the rake-structure forward longitudinal raking strokes and elevated non-raking rearward strokes and by imparting to the stopper construction downward movement when the 65 rake-structure is in the region of the end of its 70 forward stroke and upward movement when the 75

rake-structure is in position to start a succeeding forward raking stroke, guide means operatively disposed between the inclined deck on the one hand and the stopper construction on the other hand for guiding said stopper construction during the upward and downward movements thereof, said guide means being constructed so as to support the stopper construction against movement in a rearward longitudinal direction but so as to permit yielding of the stopper construction in a forward longitudinal direction; said common means for actuating the rake-structure and the stopper construction embodying a horizontally and transversely extending shaft carrying a crank rotatably mounted in journals fixed in respect to the inclined deck; and a connecting rod comprising telescoping sections having compression spring means disposed between them for normally holding the telescoping sections in extended position effective to permit under abnormal conditions foreshortening of the connecting rod upon the rake-structure encountering an abnormal resistance during a non-raking rearward stroke thereof with the one telescoping section being actuated from the free end of the crank while the other section is pivotally connected to a portion of the rake structure.

12. Classifying apparatus, comprising a tank having an inclined bottom normally partially submerged, a raking blade structure having a series of raking blades substantially parallel to one another, means for moving said structure in a substantially longitudinal closed path whereby the blades thereof convey burdens of settled solids stepwise upwardly to emergence along the inclined bottom on the forward stroke, but are out of burden conveying relationship on the rearward stroke, means providing interceptor blade elements movable toward and away from the inclined bottom, and means for controlling such transverse movement of the interceptor blade elements in timed relationship with respect to the operation of said raking blades, so as to intercept blade burdens substantially at the end of the raking stroke and to hold said burdens to prevent substantial retrogression thereof down the inclined bottom during the non-raking rearward stroke of the raking blades, at least one of said interceptor blade elements being individually functionally coordinated to and disposed and operative within a space defined by a pair of successive raking blades, said interceptor blade element thus being individually confined between one raking blade forwardly and one raking blade rearwardly thereof.

13. Apparatus according to claim 12, in which said pair of successive raking blades has non-intersecting paths of travel.

14. Apparatus according to claim 12, in which said pair of successive raking blades has paths of travel which do not intersect and which are not intersected by the transverse paths of movement of the interceptor blade elements.

15. Apparatus according to claim 12, in which the successive raking blades of said pair are spaced from one another a distance which is in excess of the raking stroke, the excess being substantially at least an amount corresponding to the aggregate thicknesses of a raking blade and of an interceptor blade element.

16. Apparatus according to claim 12, in which the interceptor blade elements are assembled and combined in a unitary bodily movable structure.

17. Apparatus according to claim 12, in which

the interceptor blade elements reciprocate substantially in planes at right angles to the bottom and in which the raking blades during the final phase of their downward movement have abrupt descent also in planes at right angles to the bottom.

18. Apparatus according to claim 12, in which the interceptor blade elements are assembled and combined in a unitary bodily movable structure which is given downward movement when the raking blade structure is in the region of the end of its forward raking stroke, and given upward movement substantially at a time when the rake structure is in a position to start a succeeding forward raking stroke.

19. Apparatus according to claim 12, in which the interceptor blade elements are assembled in a unitary bodily movable structure, with the ad-

dition of guide means operatively disposed between the inclined bottom on the one hand and said interceptor blade structure on the other hand for guiding said structure during the upward and downward movements thereof.

20. Apparatus according to claim 12, in which a series of interceptor blade elements are combined in a unitary construction operatively mounted with respect to the tank in a manner to permit a forward yielding movement thereof; with the addition of guiding means comprising a path-defining guide member fixed relative to the inclined bottom and disposed so as to support the interceptor blade construction against movement in a rearward longitudinal direction, but so as to permit yielding of the construction in a forward longitudinal direction.

CHARLES H. SCOTT.
